UNITED STATES PATENT OFFICE.

ROLAND A. NICHOLS, OF WINTERHAVEN, FLORIDA, ASSIGNOR OF ONE-HALF TO SCOTT MORRIS, OF WINTERHAVEN, FLORIDA.

MAUSOLEUM.

Application filed November 14, 1921. Serial No. 515,076.

To all whom it may concern:

Be it known that I, ROLAND A. NICHOLS, a citizen of the United States, residing at Winterhaven, in the county of Polk and 5 State of Florida, have invented certain new and useful Improvements in Mausoleums, of which the following is a specification.

This invention has reference to improvements in mausoleums, and other like structures for the reception of dead bodies, and it primarily has for its purpose to provide 10 an improved construction of mausoleum that is especially designed for the preservation and sanitation of the dead from decay and 15 the protection of the living from seepage infection.

Another object of my invention is to provide an improved construction of mausoleum or the like, for the reception of the 20 dead, in which is included a system of assemblage or building up of the parts, that constitutes the finished structure, that will provide for a large number of body reception compartments or crypts, each so de- 25 signed that there will be little seepage from a body that has been properly prepared for entombment and the menace of said body seepage provided against by a floor construction which ensures that all exudations 30 from the crypts is first filtered and then received, by gravitation, into a sealed container located under the foundation of the floor of the lowest one of the series of crypts, when such crypts are arranged in 35 vertical relation.

With other minor objects in view, which will become apparent as the description of the construction of my mausoleum follows, my said invention consists in the means and 40 the structural elements hereinafter set out in the following detailed description, as specifically mentioned in the appended claims and illustrated in the accompanying drawings, in which:

45 Figure 1 is a horizontal section, parts being in plan view, of a complete crypt or body container constructed in accordance with my invention, portions of adjacent crypts being also shown.

50 Figure 2 is a longitudinal section of a mausoleum composed of a number of crypts or separate body receiving compartments arranged in vertical relation.

55 Figure 3 is a horizontal section of the front or receiving portion of a crypt or

body receiving compartment and it illustrates more particularly the peculiar arrangement and application of a front sealing slab, and the disinfectant inlet trap hereinafter specifically mentioned. 60

Figure 4 is a front elevation of the parts shown in Figure 3.

Figure 5 is a detail view that illustrates the manner in which the disinfectant inlet pipe and an adjacent beveled corner of the 65 front or sealing slab are sealed after injecting the formaldehyde, or other substance, into the crypt.

Figure 6 is a detail view of a portion of one of the seepage offtake or drainage pipes 70 and a receiver into which it conveys the drainage.

Figure 7 is a detail cross section of a portion of the crypt floor and the upper end 75 of the drainage pipe that connects therewith.

Figure 8 is a diagrammatic plan view that illustrates a modified arrangement of my mausoleum improvements.

Figure 9 is a longitudinal section of the 80 modified arrangement shown in Figure 8.

Figure 10 is a detail view of the seepage pipe connection in the modified form shown in Figure 8.

Figure 11 is a detail view of the disinfectant inlet trap shown in Figure 8. 85

In the practical development or embodiment of my construction of sanitary mausoleum, a series of crypts or body containers are arranged in sidewise and vertical relation 90 with my invention, will follow.

The crypt or body container includes a base or bottom 1 that is concaved in the direction of its length and dished to drain any body seepage that may collect on the bottom toward the front end into a longitudinal basin 2 in which is contained quick lime and which has communication with another contiguous basin in which is contained charcoal or other filtering substance, and 100 into which the seepage passes, and from which the filtered fluid matter, collected within the crypt, is drained, in the manner presently explained.

Each crypt has opposite side walls 4—4, 110

preferably concrete, which are joined by a like back wall 40 and each crypt has an open front whose opposite top and bottom edges are offset, as at 5, to form edge bearings for 5 the reception of a front concrete slab 6 that constitutes the front closure for the crypt and the said slab, after the crypt has been charged with a preserving chemical (formaldehyde) is hermetically sealed against the 10 front of the crypt, as is indicated in the detailed Figure 5.

At the front corner, opposite the lime holding and filtering basins 2 and 3, the crypt bottom is formed with a formaldehyde 15 evaporating basin 7 that extends from the body receiving end opening of the crypt rearwardly a distance equal to the basin 2 at the opposite side.

8 designates an inlet pipe whose receiving 20 end is bent up as at 80 and is located just inside of the outer wall edges 41 of the crypt and whose inner end is embedded in the crypt bottom, and communicates through the said bottom with the basin 7, as is clearly 25 shown in the drawings.

The aforesaid basin constitutes, what is hereinafter termed the formaldehyde evaporating basin, it being understood that while formaldehyde is specifically mentioned as 30 the preserving element used, any other chemical adapted for the same purpose may be employed.

It should be here stated that the disinfectant ingredients are not injected into the 35 crypt until the said crypts are to be used, after placing a body therein, and after the front closure slab 6 is applied and sealed all around (except where the lead inlet pipe 8 is located) thus ensuring freshness and 40 strength of the disinfectant. After the charge of the combined disinfectant and preservative has been forced into the crypt, the receiving end 80 of the pipe 8 and the adjacent space between the wall 41 and the 45 edge of the front closure slab are hermetically sealed.

To provide for constant drainage from the crypt and yet maintain the crypt in a hermetically sealed condition, at all times, an 50 outflow pipe 9, preferably of galvanized iron, is built in and extends vertically of the wall, as is best shown in Figure 2, by reference to which it will be observed the upper end of the pipe 9 terminates in an inwardly 55 bent elbow 90 that projects through the inside face of the wall and communicates with the bottom of the filtering basin 3 in the crypt base.

The drain pipe 9 passes down with the 60 wall, through the base upon which the opposite side walls 4-4 of the crypt are built and with the lowermost end of the said pipe fitting and discharging into a seepage container 10, which, in practice, is preferably 65 a jug or jar which has an opening in the top

slightly larger than the outside diameter of the said discharge pipe and the latter is hermetically cemented into the said jug or jar thus forming a sealed container which retains the filtered seepage as best indicated 70 in Figure 6.

Each crypt is provided with its individual drain pipe 9 and when the mausoleum is composed of a series of crypts disposed in vertical relation, the pipes 9 for the several 75 crypts are progressively located, one foot nearer the rear end of their respective crypts and progressing from the lowest crypt to the upper one, as is clearly shown in Figure 2 of the drawings, such arrangement of the 80 drain pipes providing for a practical placing of the containers or receivers 10 below the floor of the bottom crypt.

In Figures 8 and 9, is illustrated a somewhat modified arrangement of my construction of crypt and in this latter form, the bottom of the crypt is provided with oppositely located longitudinal bridge walls 11-11 that form rests for the casket when the crypt is put to use, and the said opposite 90 bridge walls extend from the front opening of the crypt to near the rear end thereof, the rear end of the said walls merging with a cross or end wall 11^a.

In this form, the formaldehyde basin extends the full length of the crypt and around the back wall 11^a, the dished or concaved portion of the crypt bottom being located between the bridge walls 11, one of which, adjacent the basins 2 and 3, has a passage 12 100 that opens into the lime holding basin 2.

When arranged as shown in Figures 8 and 9, the crypts are disposed in adjacent pairs, that is,—the lime and charcoal holding basins of the two crypts are adjacently 105 disposed at the outer end of one dividing wall 4 and in this form a single drain pipe 9 is used for draining two adjacent horizontal crypts and the said pipe has the upper end provided with a pair of oppositely disposed receiving laterals 91 which open into the basins 3, at their respective sides of the wall. When a single pipe 9 is used, as 110 stated for draining a pair of crypts, the laterals that project into the basins 3 are sealed in any suitable manner, which seals 115 are broken only, as the crypts are brought into use so that when one of a pair of adjacent crypts is being used, the other adjacent crypt will be sealed from communication 120 with the crypt being used.

From the foregoing description, taken in connection with the accompanying drawings, the complete construction, the manner in which the parts are adapted for being operatively assembled and the advantages of my invention will be readily apparent to those familiar with the practical development and building of crypts or other like sanitary systems for burial vaults. 130

My improved system of constructing a crypt or burial vault differs from the usual arrangement of vaults that have provision for applying formaldehyde for deodorizing the escaping gases from decomposing bodies and rendering the said gases harmless, in that it contemplates the use of a quantity of formaldehyde, or other volatile chemical of similar properties injected into an open evaporating basin within the crypt after the crypt is all sealed except the lower corner of the front thereof through which the deodorizer is injected and where the inlet of the injector pipe is exposed.

When the surrounding edges of the closure seal is completely sealed, the aforesaid chemical inlet is sealed by the same operation.

The chemical supercharges the air in the crypt until it can take up no more moisture and consequently the body can give off no more moisture. The germs of putrefaction are destroyed and cease to cause decay and the body constantly remains natural and unchanged.

What I claim is:—

1. A burial crypt comprising a hollow compartment having a discharge opening and whose bottom is shaped for directing the seepage to the said discharge opening, means for draining the seepage through the said opening and exteriorly of the compartment, devices combined with the compartment through which a deodorizing solution can be injected into the said compartment and further means hermetically sealing the said compartment and the said devices after the compartment has been charged with the aforesaid solution, the said compartment bottom including a basin at the inlet side into which the deodorant solution is received, and other basins at the discharge side of the compartment, the said basins at the discharging side being adapted for the reception of chemicals that tend to consume and filter the seepage as it passes to the discharge basin.

2. In a burial vault, a crypt having a body receiving opening at one end, a slab that constitutes a closure for the said opening after the body is placed into the crypt, means for securing the said slab air-tight over the said opening, a chemical disinfectant collecting basin at one side of the crypt bottom adjacent the front end, a trap in the front wall of the crypt that discharges into the said disinfectant collection basin and whose inlet end is exposed to receive a charge of chemical disinfectant after the body is placed within the crypt and the front end thereof is closed by the slab, a filtering basin in the bottom of the crypt at the front end at that side opposite the disinfectant col-

lecting basin, the bottom of the crypt being surface shaped to convey the seepage to the filtering basin, a discharge in the crypt wall in connection with the filtering basin, and a seepage draining duct that conveys the seepage of the crypt, and means for sealing the inlet for the disinfectant sealing trap.

3. In a burial vault, a body receiving compartment containing a seepage discharge basin and means in communication with the said compartment for injecting a deodorant charge from the outside of the compartment into the said compartment after the body is placed therein, a closure for the body entrance to the said compartment, means hermetically sealing the said closure and the deodorant injecting means after the compartment has been chemically charged, a seepage receiver below the bottom of the vault, a duct connecting the seepage discharge basin from the compartment with the seepage receiver, the surface of the bottom of the said compartment being dished from the deodorant entrance to the said discharge basin whereby seepage within the said compartment is constantly drained towards the said discharge basin, means at the compartment discharge basin for filtering the said seepage as it passes to the discharge basin, the said means comprising collecting basins in the compartment for containing consuming and filtering substance.

4. A mausoleum structure of the character described comprising a crypt whose bottom is provided with a disinfectant receiving and vaporizing basin located at one side thereof, a trap which opens through the front walls of the crypt into the aforesaid basin and whose inlet is adapted to receive an injected disinfectant solution for charging the crypt, a filter in one corner of the crypt in communication with the floor space and a drain pipe in the wall of the crypt whose receiving end opens into the bottom of the filter and a receiver below the crypt bottom into which the drain pipe discharges.

5. A mausoleum structure of the character described comprising a crypt, a disinfectant solution receiving and vaporizing basin at one side of the front end of the crypt bottom, a passage through the front wall of the crypt that leads into the aforesaid basin and which has its inlet exposed beyond the front wall of the crypt for receiving an injected disinfectant solution for charging the crypt, a filter located in the opposite side of the crypt bottom in communication with the floor surface of the crypt, a ground drain pipe whose receiving end opens into the bottom of the aforesaid filter.

ROLAND A. NICHOLS.
